UNITED STATES PATENT OFFICE.

OTTO M. BERGMAN, OF ROCHESTER, NEW YORK.

HYDROAEROPLANE.

1,263,192.

Specification of Letters Patent. Patented Apr. 16, 1918.

Application filed October 13, 1917. Serial No. 196,417.

To all whom it may concern:

Be it known that I, OTTO M. BERGMAN, a subject of the King of Sweden, residing at Rochester, in the county of Monroe and 5 State of New York, have invented certain new and useful Improvements in Hydro-aeroplanes; and I do hereby declare the following to be a full, clear, and exact description of the invention, such as will enable 10 others skilled in the art to which it appertains to make and use the same.

This invention relates to a hydro-aeroplane.

The object of the present invention is to 15 provide a simple, practical and efficient hydro-aeroplane of strong, durable and comparatively inexpensive construction designed for running or skimming over the top of the water and also for flights in the air 20 and capable of starting and landing both on the ground and on the water.

A further object of the invention is to provide a hydro-aeroplane of this character adapted for use at seaside resorts as a pleasure 25 car and also for use as a passenger carrying ocean going car and capable of enabling the means for propelling it on the surface of the water to be utilized in starting the machine for flying purposes, especially 30 when the machine is made for carrying a relatively large number of passengers or a large amount of merchandise.

With these and other objects in view, the invention consists in the construction and 35 novel combination of parts hereinafter fully described, illustrated in the accompanying drawings and pointed out in the claim hereto appended; it being understood that various changes in the form, proportion, 40 size and minor details of construction, within the scope of the claim, may be resorted to without departing from the spirit or sacrificing any of the advantages of the invention.

45 In the drawings:

Figure 1 is a front elevation of a hydro-aeroplane constructed in accordance with this invention.

Fig. 2 is a side elevation of the same.

50 Fig. 3 is a plan view.

Figs. 4 and 5 are detail views illustrating the construction of the ball bearings.

Like numerals of reference designate corresponding parts in all the figures of the 55 drawings.

In the accompanying drawings, in which

is illustrated the preferred embodiment of the invention, the machine comprises in its construction a frame 1 constructed of tubes or pipes and connecting couplings 2 and 60 the said frame, which may be made of any desired size and constructed of any suitable metal, is preferably braced at opposite sides by crossed braces 3 and reinforced by side trusses 4 located at the upper portions of 65 the sides of the frame as clearly shown in Fig. 2 of the drawings.

The machine is equipped with hollow cylinders or wheels 5 and 6 located at the front, center and rear portions of the frame and 70 disposed in pairs, the members of the several pairs being arranged in spaced relation to provide a central longitudinal space 7 centrally of the frame for the accommodation of the passengers, and the motors and 75 other mechanism with which the machine may be equipped. The front and intermediate wheels are of the same construction and the rear wheels or cylinders 6 are preferably provided with paddles or blades 8 80 for enabling the rear wheels to operate as driving wheels and to effectively propel the machine on the surface of the water. The wheels or cylinders, which may be made of any desired size, can be constructed of any 85 suitable material, thin metal being preferably employed, and air may be exhausted from the same to form vacuums for reducing the weight, or they may be filled with a gas lighter than air. The wheels or cylinders 90 are provided at their sides or ends with suitable trunnions or journals 9 and are preferably mounted in ball bearings 10 of any desired construction.

The rear driving wheels or cylinders are 95 equipped with pulleys 11 and are connected by belts 12 with pulleys 13 mounted on the shaft 14 of an electric motor 15 adapted to be operated for driving the machine over the surface of the water and also for starting the machine to assist front propellers 16 and 17 when the machine is preparing to make a flight in the air. The propeller 16 is centrally arranged at the front of the machine and is mounted on the shaft 18 of 100 a motor 19 which may be an internal combustion engine or any other type of motor or engine. The propellers 17 are mounted on shafts 20 and are located above and at opposite sides of the central propeller 16, 110 as clearly shown in Fig. 1 of the drawings, and the said shafts 20 are connected with the

motor shaft by belts 21 and 22, the belt 22 being crossed so that the side propellers are driven in opposite directions. The belts 21 and 22 are arranged on suitable pulleys 23 and 24, but any other form of gearing may be employed for transmitting motion from the motor to the propellers and to the rear driving wheels.

The machine is equipped with front and 10 rear supporting planes 25 and 26 and it has a rudder 27 which may be operated by any suitable means and if desired adjustable side planes may of course be employed. The supporting planes 25 and 26 are arranged 15 above the front and rear portions of the frame and are supported by rods 27^a and suitable braces 28 and 29. Any suitable bracing means may of course be employed and the size of the planes will be proportioned to the load to be carried.

The machine is adapted for pleasure purposes at seaside resorts and also for use as a passenger carrying machine and may be advantageously employed in sighting 25 submarines as it will skim rapidly over the surface of the water and also fly through the air and, owing to the separate motors, the machine may be rapidly and easily controlled and a high rate of speed may be

attained with a maximum safety. The hollow cylinders or wheels, which are both air tight and water tight, constitute buoyant rotary elements and, while the driving mechanism is shown connected with the rear wheels or cylinders, the paddles and the motor may be applied to any of the wheels or to all of the same as will be readily understood.

What is claimed is:

A machine of the class described including a frame, front, intermediate and rear hollow cylinders arranged in pairs and disposed in spaced relation, the rear cylinder being provided with blades, a motor located between the rear cylinders and connected 40 with the same, front and rear supporting planes carried by the frame, center and side propellers located at the front of the frame, a motor having a shaft carrying the central propeller, and means for connecting the side 45 propellers with the motor.

In testimony whereof I affix my signature in presence of two witnesses.

OTTO M. BERGMAN.
